RADIATOR CAP WITH PRESSURE RELEASE
Michael J. Wilson, Chicago, Ill., assignor to Wayne Metalcraft Company, Chicago, Ill., a corporation of Illinois

Filed May 27, 1963, Ser. No. 283,286
5 Claims. (Cl. 220—44)

This invention relates to an improved automotive vehicle radiator cap and it particularly relates to a radiator cap having means for manually releasing the pressure in the vehicle radiator before removing the cap from the radiator.

Automotive vehicle engines are commonly cooled by water circulating through a radiator. In order to provide improved cooling efficiency, it is normal practice to pressurize the cooling system, the pressure being maintained by closing the radiator spout with a cap. Such caps ordinarily carry a sealing means which is maintained against a valve seat provided in the spout of the radiator by means of a spring. The spring allows the valve means to release pressure from the radiator when the radiator pressure exceeds the pressure exerted by the spring.

When it is desired to remove the cap from the radiator and when the coolant is at a high temperature and under pressure, great care must be exercised in removing the cap from the radiator. Unless such care is used, the pressurized hot coolant is likely to be suddenly discharged from the spout of the radiator and to seriously burn the person removing the cap. Clearly, it would be highly advantageous to provide means for manually releasing the pressure in an automotive vehicle radiator before the cap is removed from the radiator so as to avoid the danger of injuring the person removing the cap.

It is therefore a primary object of this invention to provide an automotive vehicle radiator cap having means for releasing the pressure in the radiator before the cap is removed from the radiator.

It is a further object of this invention to provide a valve controller on a radiator cap which serves an additional function as means for applying connecting and disconnecting screw forces or torque to the radiator cap during connection and disconnection of the cap to a radiator spout.

It is another object of this invention to provide a valved radiator cap for pressurized cooling systems wherein the valve is automatically moved to normally open or normally closed condition depending upon the normal actuation of the radiator cap, but which additionally permits of selective actuation of the valve.

It is an additional object of this invention to provide a radiator cap having pressure release means which is characterized by its simplicity and economical construction.

Further purposes and objects of this invention will appear as the specification proceeds.

One embodiment of the present invention is illustrated in the accompanying drawings, wherein:

FIGURE 1 is a vertical sectional view of my improved radiator cap in position on an automotive vehicle radiator with the pressure release means in the closed position;

FIGURE 2 is a sectional view taken along line 2—2 of FIGURE 1;

FIGURE 3 is a view similar to FIGURE 1, except that the pressure release means is shown in the open position;

FIGURE 4 is a fragmentary sectional view taken along line 4—4 of FIGURE 1; and

FIGURE 5 is a bottom plan view of my radiator cap.

The automotive vehicle radiator 10 includes a spout 12 which is secured to the radiator 10 at 14, as by welding. The spout 12 includes a lower flange 16 having an

2

annular valve seat 18 and an upstanding, generally cylindrical side wall 20 which defines a chamber 21. The side wall 20 has a vent tube 22 which opens into the chamber 21. The side wall 20 terminates with an upper flange 24 having an annular raised seat 26. The flange 24 includes a depending skirt portion 28 which is provided with opposed recesses 30.

The radiator cap, generally 31, is provided with a generally circular rigid support member 32. The support member 32 is provided with a depressed central portion 34 having an aperture 35. As best shown in FIGURES 4 and 5, the support member 32 includes a tongue 36 and retaining portion 37 which is positioned opposite to the tongue 36. The support member 32 also includes a pair of opposed, downturned side walls 38, each having inturned opposed flanges 40. The flanges 40, as shown in FIGS. 1 and 3, are positioned within the recesses 30 of the skirt portion 28, and then the cap is rotated whereby the flanges move along cammed edges of the recesses 30 so as to firmly secure the cap 31 to the spout 12.

A cover 42 encompasses and is secured to the support member 32 and provides a conventional appearing radiator cap. The cover 42 includes a top 44 having depending side walls 46. Opposed recessed portions or depressions 48 are provided at the juncture of the top 44 and side wall 46. The depressions 48 are in general alignment with the inturned flanges 40 of the support member 32 and are adapted to buttress against the upper side of the support member 32 whereby a chamber 50 is provided between the cover 42 and the support member 32.

The cover 42 also includes an integral ear 52 which extends outwardly from the side wall 46 so as to provide a gripping means on the cover 42 for applying or removing the cap 31 from the radiator 10. A retaining depression 54 is provided on the outer side wall of the gripping ear 52 and is adapted to fixedly engage the lower surface of the tongue 36 of the support member 32. Positioned opposite to the gripping ear 52 in the side wall 46 is a transverse slot 56. The lower edge 57 of the slot 56 securely engages the underside of the retaining portion 37 of the support member 32. Thus, the support member 32 is firmly maintained in engagement with the cover 42 by the tongue 36 engaging the depression 54 in the ear 52, by the retaining portion 37 engaging the slot 56, and by the recessed portions 48 in the cover 42 abutting the upper side of the support member 32.

A retaining member 58 is secured to the support member 32 and is positioned in the aperture 35. Specifically, a lateral groove 60 is provided in the retainer 58 and engages the edges surrounding the opening 35. The retainer member 58 is generally cylindrical in shape and is provided with an outer side wall 62 having a lower shoulder 64 of increased diameter. The retainer 58 is also provided with an axial bore 66 having a constricted lower end 70.

Also securely mounted within the lateral groove 60 is a generally circular diaphragm member 72. The diaphragm member 72 is conveniently constructed of a thin sheet of metal, preferably brass, which has springy properties. The diaphragm 72 has a central opening 74 which is fixedly carried by the lateral groove 60 and also has an annular seat 76 which is adapted to receive one end of the coil spring 77. The diaphragm member 72 is also provided with a seat 78 for contacting the upper side of the annular seat 26 of the spout 12. When the cap 31 is positioned on the spout 12, it is biased upwardly by the springable diaphragm member so that the inturned flanges 40 of the rigid support member 32 securely engage the recessed portions 30 of the skirt 28 of the spout 12. The annular terminal portion 78 of the diaphragm 72, which contacts the seat 26 of the spout 12 provides metal to metal contact which, although not providing a high pressure seal,

does provide sufficient sealing for substantially preventing the hot coolant from passing therethrough and for causing the hot liquid to pass through the vent tube 22 provided in the wall 29 of the spout 12.

A slidable member 80 is mounted on the outer wall 62 of the retaining member 58 and has an upper wall 82 with a plurality of vents 86 which allow free communication between the interior of the slidable member 80 and the spout chamber 21. The slidable member 80 includes an intermediate flange 84, located between and connected to an upper generally cylindrical side wall 88 and a lower generally cylindrical side wall 90. The intermediate flange 84 is adapted to receive the lower end of the coil spring 77 and the upper side wall 88 laterally supports the coil spring 77 which biases the slidable member 80 downwardly. The lower side wall 90 is provided with an out-turned bottom flange 92 adapted to secure a gasket backup plate 94 to the slidable member 80.

The gasket backup plate 94 is secured to the flange 92 by means of a plurality of retaining fingers 96 which are crimped to the flange. The backup plate 94 includes a central opening 98 and a raised annular portion 100 and provides a rigid backing for the gasket 102.

Mounted adjacent to the underside of the backup plate 94 is a sealing member or gasket 102 which is biased into sealing engagement with the seat 26. The gasket 102 is constructed of suitable gasketing material but is to be resistant to high temperatures. The gasket 102 has a central opening 104, aligned with the opening 98 in the backup plate 94, and is secured to the backup plate 94 by an eyelet 106 which passes through both openings. The eyelet 106 is staked at one end to the gasket 102 and at the other end to the backup plate 94.

A pressure relief valve 108 is centrally carried by the backup plate 94 and is adapted to release pressure from the radiator 10 and also to provide atmospheric pressure to the radiator 10 when a vacuum exists within the radiator. The relief valve 108 includes a relief valve retaining member 110, a sealing member 114 and a leaf spring 120 which biases the sealing member 114 into contact with the lower side of the gasket 102.

The valve retainer 110 includes shoulder portion 112 which contacts the upper surface of the leaf spring 120, thereby lifting the sealing member 114 into contact with the gasket 102.

The sealing member 114 is sealably fixed to the valve retainer 110 at the central portion of the lower wall 115. The diverging side wall 116 extends from the wall 115 upwardly toward the gasket 102 and includes an annular valve seat 118 which is adapted to seal the lower surface of the gasket 102.

The leaf spring 120 includes legs 122, formed by down-turned corners, which contact the raised annular portion 100 of the back-up plate 94, whereby the leaf spring 120 lifts the retaining member 110 and the sealing member 114 upwardly, thereby causing the valve seat 118 to contact the gasket 102. The leaf spring 120 is adapted to only lift the sealing member 114 to the surface of the gasket 102 since the relief valve 108 also acts as a vacuum relief valve. Thus, when a slight vacuum is provided in the radiator 10, since there is only a light upward force raising the sealing member, atmospheric pressure easily forces the relief valve 108 open. Further, when the radiator is under pressure, pressure in the radiator 10, acting upwardly against the sealing member 114, forces the retaining member into firm sealing engagement with the gasket 102.

However, it is to be appreciated that the leaf spring 120 is not required for proper operation of the valve. Thus, by eliminating the leaf spring 120, when there is no pressure in the radiator 10, the sealing member 114 drops downwardly from the gasket 102, rather than remaining in contact therewith. When the radiator 10 is under pressure, the sealing member is forced upwardly into firm sealing engagement with the gasket, just as when a leaf spring 120 is used. Also, the means used for relieving

pressure in the radiator 10, which means will be subsequently described, is precisely the same whether a leaf spring 120 is used or is not used.

A relief valve actuating means 123 is provided for opening the relief valve 108 when the cap 31 is to be removed from the radiator 10 at a time when the coolant is hot and under pressure. Specifically, the actuating means 123 includes a push rod 124 reciprocally positioned within the bore 66 of the retaining member 48. The lower end of the push rod 124 is aligned with the upper side of the valve retainer 110 and, when the rod is pushed downwardly, it opens the valve 108 by pushing the sealing member 114 away from sealing engagement with the gasket 102. The push rod 124 is also provided with an upper shoulder 126 which slides in the bore 66. A coil spring 128 carried by the retainer 58 normally biases the push rod 124 upwardly.

It is an important feature of the invention that cam means 130 be provided for operating the actuating means 123 and the relief valve 108. The cam means 130 includes an elongated arm 132 which is located in the chamber 50 between the cover 42 and the support member 32 and which is pivotally secured to the tongue 36 of the support member 32 by a shouldered rivet 134. The movable end of the arm 132 includes an extension 136 which passes through the transverse slot 56 provided in the side wall 45 of the cover 42. A handle 138 is mounted on the extension 136 and is shaped similar to the gripping ear 52 provided on the cover 42. The cam arm 132 is pivotable on an axis which is generally parallel to the axis of the cap 31, the axis of the push rod 124 and the axis of the retaining member 110, or is pivotable in a direction transverse to the axis of the cap 31. The pivoting movement of the arm 132 is limited by the dimensions of the slot 56 in the cover 42.

The arm 132 is shaped to define a cam 140 which is operatively aligned with the upper end of the push rod 124 and, as shown best in FIGURES 1 and 3, the cam 140 includes a slanted cam portion 142 connecting the lower dwell portion 144 to the upper dwell portion 146. When the cam 140 is in the position of FIGURE 1, the upper end of the push rod 124 abuts the upper dwell portion 146 by the biasing action of the spring 128, thereby allowing the radiator 10 to be maintained under pressure. When it is desired to remove the cap 31 from the radiator 10, the arm 132 is pivoted in the same direction required to remove the cap 31 from the radiator 10, normally a counterclockwise direction, and the upper end of the push rod 124 rides downwardly along the slanted cam portion 142 until reaching the lower dwell portion 144, as shown in FIGURE 3. During this downward movement, the lower end of the push rod 124 comes into contact with the upper side of the valve retainer 110 causing it to move downwardly, whereby the pressure in the radiator 10 is relieved through the opening between the sealing member 114 and the gasket 102, through the annular channel 121 between the eyelet 106 and valve retainer 110, through the vents 86 of the slidable member 80 into the spout chamber 21, and finally out to the atmosphere through the vent tube 22 in the spout 12. The cam means 130 is locked in the open position by the biasing action of the spring 128 causing the upper end of the push rod 124 to firmly engage the lower cam portion 144.

In summary, it is seen that the above-mentioned invention accomplishes all of the aforementioned objects. When it is desired to remove the above-described radiator cap from a radiator, a person merely rotates the cam arm 132 by the handle 138 in the direction that is required to remove the cap 31 from the radiator 10, whereby the pressure in the radiator 10 is relieved through the vent 22. The cam means 130 is adapted to remain in the open or closed position until returned manually to the opposite position. To replace the cap on the radiator, the operator merely rotates the cap and arm 132 in the direction required to replace the cap, normally in a clockwise direc-

tion, thereby causing the cam means 130 to be returned to and locked in the closed position for maintaining pressure in the radiator 10.

While in the foregoing there has been a detailed description of one embodiment of the present invention, it is to be understood that all equivalents obvious to those having skill in the art are to be included within the scope of the invention, as claimed.

What I claim and desire to secure by Letters Patent is:

1. A cap for an automotive vehicle radiator having a spout which includes a lower seat and a vent positioned above said lower seat, said cap comprising, in combination: a support member, a cover secured to said support member and having a central portion of said cover spaced from said support member to define a chamber therebetween, said cover having an ear projecting from one side for assisting in gripping said cap and also having a transverse slot positioned opposite said ear member, means for securing said support member to said spout, means for sealing the lower seat of said spout, a relief valve positioned centrally of said sealing means, means for opening said relief valve, and cam means pivotally carried by said support member, said cam means including an elongated arm extending through said chamber and having a movable end extending through the slot in said cover and also having a cam portion positioned in said chamber in operating alignment with the upper end of said opening means, whereby the pressure in said radiator is relieved through said relief valve into the vent in said spout in response to the downward movement of said opening means against said relief valve upon pivoting said arm.

2. A radiator cap for the radiator spout of a pressurized liquid cooling system comprising, in combination: cap means for attachment to a radiator spout, said cap means including a support member and a cover secured to said support member with portions of said support member and cover spaced from each other to define a chamber therebetween, a valve member carried by the cap means and adapted to be normally biased toward a closed position by being exposed to pressure developed in the radiator, movable means carried by the cap means for selectively moving the valve member to an open position against the pressure to which the valve member may be exposed, a portion of said movable means entering said chamber to be engaged therein, cam means in said chamber for engaging and selectively operating said movable means, and a movable lever extending into said chamber and cooperating through said cam means with said movable means at one position of said lever to effect opening of the valve member and at another position of said lever to permit closing of said valve member.

3. A radiator cap for the radiator spout of a pressurized liquid cooling system comprising, in combination: cap means for attachment to a radiator spout and defining a chamber therein, a valve member carried by the cap means and adapted to be normally biased toward a closed

position by being exposed to pressure developed in the radiator, movable means carried by the cap for selectively moving the valve member to an open position against the pressure to which the valve member may be exposed, a portion of said movable means entering said chamber to be engaged therein, cam means in said chamber for engaging and selectively operating said movable means, a movable lever extending into said chamber and cooperating through said cam means with said movable means at one position of said lever to effect opening of the valve member and at another position of said lever to permit closing of said valve member, spaced elements on said cap means for limiting the range of movement of said lever substantially to encompass the said two positions of the lever, there being a fixed gripping ear on said cap means, and a handle on said lever located substantially diametrically of said fixed gripping ear, so that said handle serves both as a means for moving the lever and as a gripping ear for the radiator cap.

4. A device as in claim 3 wherein said lever is elongated and is pivoted adjacent one end thereof on said cap means adjacent the fixed gripping ear, the cam means being defined on an intermediate portion of the lever, and the cap means defining an elongated slot through which the other end of the lever extends with the ends of the slot defining the said spaced elements.

5. A radiator cap for the radiator spout of a pressurized liquid cooling system comprising, in combination: cap means for attachment to a radiator spout, a valve member carried by the cap means and adapted to be normally biased toward a closed position by being exposed to pressure developed in the radiator, movable means carried by the cap for selectively moving the valve member to an open position against the pressure to which the valve member may be exposed, a movable lever cooperating with said movable means at one position of said lever to effect opening of the valve member and at another position of said lever to permit closing of said valve member, spaced elements on said cap means for limiting the range of movement of said lever substantially to encompass the said two positions of the lever, there being a fixed gripping ear on said cap means, and a handle on said lever located substantially diametrically of said fixed gripping ear, so that said handle serves both as a means for moving the lever and as a gripping ear for the radiator cap, and the forces applied to said handle during attachment of the cap operating to automatically permit closing of the valve member while forces applied to said handle during removal of the cap operating to automatically effect opening of the valve member.
